CLAIM

The ornamental design for a smart panel, as shown and described herein.

DESCRIPTION

FIG. 1 is a front elevation view of a smart panel showing our new design;

FIG. 2 is a left side elevation view thereof;

FIG. 3 is a right side elevation view thereof;

FIG. 4 is a top elevation view thereof;

(Continued)

FIG. 5 is a bottom elevation view thereof; and,
FIG. 6 is a rear elevation view thereof.

The broken lines of the smart panel depict environmental structure or portions thereof, and form no part of the claimed design.

1 Claim, 6 Drawing Sheets
